UNITED STATES PATENT OFFICE.

JAMES A. CUNNINGHAM, OF INDEPENDENCE, KANSAS.

HOSE-COUPING.

1,153,895.

Specification of Letters Patent. Patented Sept. 21, 1915.

Application filed June 19, 1915. Serial No. 35,042.

To all whom it may concern:

Be it known that I, JAMES A. CUNNINGHAM, a citizen of the United States, residing at Independence, in the county of Montgomery and State of Kansas, have invented a new and useful Hose-Coupler, of which the following is a specification.

The present invention appertains to a connector for connecting the hose sections of two railroad cars, and aims to provide a novel and improved device whereby the hose sections are automatically coupled together when the cars are coupled, to thereby bring the pipe sections of the cars into communication without manual attention.

The present connector embodies coöperating heads to which the hose sections are connected, novel means for guiding the heads into proper abutment when the cars are brought together, so that the hose sections will be brought into communication, and means for yieldably and adjustably supporting said heads in order that they will properly meet each other.

It is also within the scope of the invention to provide a hose connector of the nature indicated, which is comparatively simple and inexpensive in construction, which may be readily applied to various freight cars and passenger coaches, and which will be thoroughly practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

Figure 1 is a side elevation of the improved connector. Fig. 2 is a face view of one of the heads of the device. Figs. 3 and 4 are sectional views taken on the lines 3—3 and 4—4, respectively, of Fig. 2. Fig. 5 is a reduced fragmental elevation of the head.

In carrying out the invention, the adjacent ends of the two cars or coaches each carry a connector or coupling head, and to this end clamps 1 are engaged to the draw bars 2 of the car couplers, and have depending arms or rigid hangers 3. Horizontal

arms or bars 4, which project toward one another, are adjustably carried by the lower or free end portions of the hangers 3, the arms 4 being provided with a longitudinal series of apertures 5 through which bolts 6 are engageable, said bolts being carried by the hangers 3 for clamping the arms 4 to the hangers.

Coiled wire expansion springs 7 are mounted upon or surround the free portions of the arms 4 and project beyond the free ends of the said arms, the projecting or free ends of the springs 7 being secured to and carrying the connector heads 8. The connector heads 8 are arranged in an upright position, and are adapted to abut against one another when the cars are coupled together.

As illustrated, the appliance is adapted for use on passenger coaches, which necessitates a plurality of connections being made, but it is to be understood that the appliance may also be employed upon freight cars, as will hereinafter more fully appear.

Removable sections 9 rest against and are attached to the upper and lower ends of the heads 8, the sections 9 having portions 10 straddling the ends of the heads 8 and overlapping the sides of the said heads, and bolts or other securing elements 11 are engaged through the portions 10 and take into the heads 8 for clamping the sections 9 to the heads.

The heads 8 each have a bore 12 extending therethrough, and the sections 9 each have a bore 13 extending therethrough. The bores 12 and 13 of the two heads are arranged to align with each other when the heads are brought together, and suitable gaskets 14 are secured to or embedded within adjacent faces of the heads 8 and their sections 9 at the respective ends of the bores, whereby the gaskets 14 of the two heads are arranged to fit tightly together to prevent leakage. Nipples 15 and 16 are threaded into those ends of the respective bores 12 and 13 opposite the gaskets 14, and the hose sections 17 and 18 are connected to the respective nipples 15 and 16. The hose sections 17 are connected to the train pipe sections of the coaches, while the hose sections 18 are connected to the steam and whistle pipe sections, or other pipe sections carried by the coaches.

Safety chains 19 are preferably attached to the heads 8 and to the sills of the coaches.

In order to guide the heads 8 properly into abutment and alinement when the heads 8

are brought together, a plate 20 is secured to one side of each head 8 and is provided with an angularly extending wing 21. This wing 21 is arranged obliquely, and projects to one side, and is provided with a V-shaped recess 22, the crotch portion of which is arranged adjacent the head 8. The recess 22 provides two arms 23, and the wing 21 is provided with a relatively narrow slot 24 extending from the crotch portion of the recess 22. The head 8 carries an angularly extending rod 25 projecting obliquely from the side of the head 8 opposite the wing 21. The wing 21 and rod 25 diverge from the face of the head 8, and the rod 25 is arranged directly opposite the slot 24.

The guiding elements of the two heads 8 are reversed, due to the fact that the heads are disposed in opposite directions, and the wing 21 and rod 25 of one head will coöperate with the rod and wing, respectively, of the other head, for properly guiding and holding the heads.

When the cars are separated, the heads 8 will be projected slightly due to the expansion of the springs 7, and when the cars are coupled, the heads 8 abutting against one another will be moved against the springs 7, to hold the heads 8 tightly against one another, and with sufficient tension to prevent leakage. The springs 7 also allow the heads to yield in various directions, in order that the heads may be properly brought into co-operation. The arms 4 may be adjusted for adjusting the normal positions of the heads 8 when the heads are released, in order that the appliance operates properly.

When the heads 8 move toward one another, the rods 25 of the heads will be received by the recesses 22, and the edges of the arms 23 defined by the recesses 22 will direct the rods 25 into the slots 24 whereby the heads 8 are alined with one another so that they will meet properly. In this manner, the heads are guided in a simple and effective manner into coöperative relation, and when the rods 25 are received by the slots 24, the heads 8 will be firmly held in engagement with one another without the liability 50 of the heads oscillating or being displaced

laterally. The diverging guide elements of one head in receiving the other head will also assist in swinging the heads into alinement, as will be apparent.

When the device is used upon freight cars, 55 the hose sections 18 are not employed, and the sections or attachments 9 are detached from the heads 8, whereby the hose sections 17 only are connected.

The various advantages and attributes of 60 the invention will no doubt be obvious to those skilled in the art, in view of the foregoing, taken in connection with the drawing, and further description is not deemed necessary. 65

Having thus described the invention, what is claimed as new is:

1. In a hose connector, a pair of heads adapted to abut against one another, means for yieldably supporting said heads, 70 detachable sections attached to said heads and arranged to aline with one another, the heads having coöperating means for guiding the heads into abutment with one another, the heads and sections having bores adapted 75 to be brought into communication, and said heads and sections having means for the attachment of hose sections thereto to communicate with said bores.

2. In a hose connector, a pair of upright 80 heads adapted to abut against one another, means for yieldably supporting said heads, the opposite sides of the head having co-operating guiding means for guiding the heads into alinement when they abut one 85 against the other, and detachable sections carried by the upper and lower ends of the heads, the heads and sections having bores adapted to be brought into communication when the heads abut against one another, 90 and the heads and sections having means for the attachment of hose sections thereto.

In testimony that I claim the foregoing as my own, I have hereto affixed my signature in the presence of two witnesses.

JAMES A. CUNNINGHAM.
